SQUEEZE BOTTLE OR SIMILAR ARTICLE

Henry Wish, Tuckahoe, N.Y.
(%3329 Merritt Ave., New York 69, N.Y.)

Filed Apr. 11, 1960, Ser. No. 60,113

Term of patent 3½ years

(Cl. D58—8)

Fig. 1 is a top plan view of a squeeze bottle or similar article embodying the invention;

Fig. 2 is a side elevational view thereof;

Fig. 3 is a cross-sectional view taken on line 3—3 of Fig. 2; and

Fig. 4 is a cross-sectional view taken on line 4—4 of Fig. 2.

The dominant features of the design are shown in full lines.

I claim:

The ornamental design for a squeeze bottle or similar article, substantially as shown and described.
